ELECTROLYTIC DEVICE

Max Knab, Brooklyn, N. Y., and Harold I. Danziger, Williamstown, Mass., assignors to Sprague Specialties Company, North Adams, Mass., a corporation of Massachusetts

Application August 4, 1937, Serial No. 153,728

5 Claims. (Cl. 175—315)

The present invention relates to electrolytic devices and more particularly to improvements in the construction of such devices.

The invention will be described in connection with wet electrolytic condensers as used in the filter circuits of radio receiving devices, but is not restricted thereto.

Electrolytic condensers of the aforesaid type consist as a rule of one or more film-forming electrodes immersed in a suitable electrolyte and having a closed and sealed metallic container. An attached extension of the electrode or electrodes, referred to as an anode riser, projects from the container for the outside connection of the electrode. In case the electrode lacks rigidity, for example when it consists of a thin foil, the riser also serves as a support for the electrode.

Various riser constructions have been suggested and used in the past, the most common being rod-shaped risers to which the electrode was attached by means of bolts, rivets, and like connecting members which pass through corresponding holes of the electrode and riser.

Such constructions have several disadvantages; for example the drilling and riveting involve added expenses and furthermore, the holes greatly weaken these members; thus to give the riser sufficient rigidity it has to be made of a substantial cross-section which further increases the manufacturing costs.

A still more serious objection to such constructions is the large number of contact surfaces incidental to them, there being contact surfaces between the electrodes and the rivets and separate contact surfaces between the rivets and the riser, which correspondingly increase the chance for corrosion at the contact surfaces.

An object of this invention is therefore to provide an electrode assembly comprising a rigid riser of great simplicity and which involves small costs of manufacture and assembly.

A further object of the invention is to provide an electrode assembly having a minimum of contact surfaces.

Other objects and novel features of the invention will appear as the specification progresses.

According to the invention the riser consists of an aluminum or other film-forming metal rod or wire which is flattened along its portion adjacent to the electrode. The flattening of this riser portion takes place by compression, which operation at the same time extrudes from the riser a number of integral projections adapted

to form rivets for the electrode. Preferably the riser is also mechanically strengthened by integral ribs forming a backing for the extruded rivets, and the rivets are provided with distancing shoulders and cutting edges for purposes later to be described.

In the drawing forming part of the specification:

Figure 1 is a partly sectionized side elevation of an electrolytic condenser embodying the invention;

Fig. 2 is a top view of the anode assembly;

Fig. 3 is a front elevation of an anode riser made according to the invention;

Fig. 4 is a side elevation of the anode riser of Fig. 3;

Fig. 5 is a rear elevation of the anode riser of Fig. 3;

Fig. 6 is an enlarged scale view of a portion of Fig. 4 showing the details of the rivet construction;

Fig. 7 is a cross-sectional view taken along the line 7—7 of Fig. 6.

Referring to the drawing, the condenser shown in Fig. 1 comprises a cylindrical metallic container 10, which preferably constitutes the cathode of the condenser, and which may be either of film-forming or non-film-forming metal. The container 10 is provided with a reduced tubular extension 12, threaded at 13 and extending into a further reduced tubular portion 14.

The anode assembly 15 consists of a corrugated thin foil 16 of aluminum or other film-forming metal, having the shape of an accordion pleating, and is secured to the anode riser 17 to be later more fully described.

The top of the container is provided with a crowned metal cap 18 which fits into the container end 11. A vent gasket 19 of suitable material, for example of wax-impregnated cloth, is interposed between the container 10 and the cap 18. The free edge of the cap 18, with the gasket 19 interposed, is crimped over the rim provided on the container 10 to form a liquid-tight seal.

To prevent the anode foil 16 from contacting with the container 10, there is interposed between same and the anode assembly 15 an insulator, for instance, a thin hard rubber cylinder 20. To permit free circulation of the electrolyte between cathode and anode, the insulator 20 is provided with perforations 21 throughout its area.

The threads 13 on the reduced neck portion 12 are adapted to receive a nut (not shown) by

means of which the condenser may be secured to a suitable base.

The extension 14 has preferably the same inside diameter as the extension 12, so that the two form a common bore 22; the wall of the extension 14 is however preferably much thinner than the wall of extension 12.

Placed in the bore 22 is a tightly-fitting plug 23 preferably of semi-hard vulcanized rubber 10 through which passes the anode riser 17.

The plug 23 is preferably of such a length as to extend on both sides of the neck portion 14. Proper sealing between the plug 23 and the neck 14 may be obtained by fluting, as described in U. S. A. Patent No. 1,996,982 to Robert C. Sprague et al.

A suitable film-maintaining electrolyte 25 is provided in the container, and fills the container close to its top.

Such an electrolyte comprises as a rule, one or more ionogens and a solvent. As ionogen preferably a combination of a weak acid and salt is used, for instance an electrolyte comprising borax and boric acid or ammonium borate and

boric acid, having as solvent water and/or a polyhydric alcohol. Various other acids and salts either alone or in combination give good results; for instance, solutions of phosphoric acid, citric acid, tartaric acid, and/or of their salts may be

used, whereby the salts do not need to be those of the acid used.

The viscosity of the electrolyte may range from that of water at 100° C. to that of a paste.

A preferred embodiment of the riser of the invention is shown in detail in Figs. 3 to 7. The riser is shaped from an aluminum rod of small diameter, having for example a diameter of $\frac{1}{8}$ ". The portion 30 contacting with the electrode 16 is flattened, whereas its downward extending portion 31 is left round.

Extruded from the section 30 are a plurality of rivets 32 which serve to fixedly hold the electrode foil 16 and make positive electrical connections therewith. The number of rivets depends particularly on the length of the foil 16; as a rule we space the rivets about 1" apart.

The rivets 32 are formed with a conical recess 50 to facilitate the riveting and to simplify the anode assembly, as will be explained later. We also prefer to form the rivets with a shoulder 33 which serves to hold the electrode foil 16 clear from the riser so that the foil can be properly filmed over its entire area except for the small portions directly held by the rivets. The clearance so obtained also prevents frictional contact between the electrode foil 16 and the riser 17, which would cause corrosion of the filmed surfaces at such contact points.

In the rear of the rivets 32 the material of the riser is so deformed as to constitute elongated cavities 34 provided with longitudinal ribs 35, which reinforce the riser 17 at its rivet-carrying portions.

As a rule, as is also indicated in the drawing, the rivet-carrying portions 41 are flattened to a greater width than are the portions 36 intermediate and adjacent thereto.

The round portion 31 of the riser is preferably provided with lengthwise corrugations 37 so lo-

cated as to engage the rubber plug 23 when assembled in the condenser, and thus to prevent axial rotation of the riser within the stopper.

To obtain a sturdy construction, we have found it necessary to form the riser with its flattened section 30, the extruded rivets 32 and shoulders 33, the strengthening rib 35, and the corrugations 37 all in one stamping operation. This forming process and the apparatus used therefor, however, does not form part of our present patent 10 application.

The portions 36 of the riser are provided with lateral corrugations 38. The corrugations 38 have no special function in the device, but are of importance in the process of making the riser. 15

In assembling the foil 16 and riser 17, the foil 16 is placed directly over the rivets 32 and the rivets are spun therethrough forming thereby their own holes in the foil with the aid of the sharp edge formed by their conical recess 50; this 20 makes it unnecessary to provide the foil beforehand with holes.

While we have described our invention in connection with specific examples and in specific applications, it should be well understood that we do 25 not wish to be limited thereto, but desire the appended claims to be construed as broadly as permissible in view of the prior art.

What we claim is:

1. In an electrolytic condenser, an anode assembly comprising a foil and a supporting riser for same, said riser having a flattened portion adjacent to the electrode foil, and a plurality of projecting portions on said flattened portion, and rivets extending from said projecting portions, 35 said projecting portions and rivets being integral with said riser and securing said foil to said riser in spaced relationship.

2. An electrode riser consisting of an aluminum wire flattened at one end, a plurality of 40 rivets integral with and extending from said flattened portion, and ribs formed on the riser in the rear of said rivets to increase the rigidity of the riser.

3. An electrode riser for electrolytic devices, 45 comprising a rod member and integral rivets formed on said rod member, said rivets being provided with distancing shoulders.

4. In the manufacture of electrolytic devices, the process which comprises, securing an electrode foil to an anode riser by piercing through said electrode foils perforations with projections provided on said riser, riveting said foil to said riser by means of said projections, and maintaining the electrode surface in non-contacting relation with the riser in its entire portion not fixedly secured to the riser.

5. In an electrolytic condenser, an anode assembly comprising a foil and a rod-shaped supporting riser for same, said riser comprising a 60 flattened portion, a plurality of offset portions provided on one side of said flattened portion, a plurality of rivets integral with and extending from said offset portions, and means to increase the rigidity of said riser, said means comprising 65 ribs formed on said flattened portion at the rear and on the opposite side of said offset portions.

MAX KNAB.

HAROLD I. DANZIGER.
